ABSTRACT: A smoking pipe bowl having an aperture in its bottom wall, with relatively thin plates of metal or the like secured in place on each side of the bottom wall in relative alignment, with central openings in each plate aligned with the bottom wall aperture. The plates are secured in place by a generally tubular metal eyelet extending through the aligned openings and having enlargements at either end sandwiching the plates and bottom wall together.

BOWL FOR SMOKING PIPES AND METHOD OF MAKING SAME

BACKGROUND

The present invention, although generally applicable to smoking pipes with bowls made of practically any wood or wood like material, is principally directed to pipes having corncob bowls, particularly pipes in which the corncob bowls are replaceable interior liner elements for metal or other outer bowls.

In corncob pipes generally, the most serious defect is the fact that the central part of the cob is of a pulpy or pithy nature, and is quite weak in comparison to the woody outer part of the cob. Consequently, corncob bowls have a tendency to burn through in a relatively short length of time. Also, the bottom walls do not withstand the scraping to which pipe bowls are typically subjected.

For these reasons, it has heretofore been proposed to strengthen the bottom wall of a corncob bowl in any number of ways, generally by securing or resting a fire grate of ceramic or metal inside of the bowl, at its bottom. To a certain extent, such approaches have been helpful, since the fire grates so used have proved the practicability of strengthening the weak central part of the corncob in this manner. However, previous structures for this purpose have not fully overcome the entire problem encountered, in that they have produced undesirably high manufacturing expense, and they also have not been suitably secured within the bowl; hence, they have tended to fall out of place after a relatively brief period of initial use, as for example at such time as the smoker knocks the bowl of his pipe against an ashtray or the like to remove ashes or partly smoked tobacco.

SUMMARY

The present invention provides a novel approach toward the underlying problem stated above, and solves this problem by the provision of a novel bowl construction in which a heat-resistant plate is located in the inside of the bowl and a reinforcing plate is disposed on the outside of the bowl, with means interconnecting the two sandwiching the bottom wall of the corncob bowl therebetween. The construction so provided has many advantages. Firstly, it is very securely retained in place, and is not subject to being dislodged by any of the normal actions to which it may be subjected during use; moreover, it very effectively strengthens the normally weak bottom wall of the corncob bowl from each side, and in effect converts the weak bottom wall to a very strong and suitable member. Furthermore, and of considerable importance, the present invention lends itself very well to rapid manufacturing techniques, and is highly economical from the standpoint of production economies.

Thus, briefly stated, the present bowl construction comprises a generally hollow bowl of corncob or the like having an aperture in its bottom wall, and apertured plates on either side of the bottom wall, in register with its opening, with means interconnecting the plates and sandwiching the bottom wall of the bowl therebetween.

DRAWINGS

FIG. 1 is a perspective of the corncob bowl;

FIG. 2 is an enlarged central section of the bowl, taken through the plane II-II of FIG. 1;

FIG. 3 is an overhead plan view of the bowl; and

FIG. 4 is a fragmentary, exploded perspective view showing the present bowl construction and tools used in the manufacture and assembly thereof.

PREFERRED EMBODIMENT

Referring more specifically to the drawings, the bowl construction 10 of the invention, seen generally in FIG. 1, includes a bowl member 12 which may take practically any desired specific form but which includes a side wall 14 and a

bottom wall 16, which together define the familiar bowl with a hollow internal cavity 18 in which a charge of tobacco is packed and smoked. As illustrated, the bottom wall 16 has an aperture extending therethrough, located generally centrally thereof.

Disposed within the internal cavity 18 of the bowl, and directly atop the bottom wall 16, is a disk-like plate element 20, which is of metal or other suitable heat-resistant material. Immediately beneath the bottom wall 16 is a second similar disk-like plate 22, which serves a reinforcing function and which should be of generally rigid material, preferably also of metal.

The two plate elements 20, 22 are held in the aforementioned position by a generally tubular fastening means 24, in the form of a metal eyelet having enlarged end extremities 26, 28 overlapping the plate elements and sandwiching them on either side of the bottom wall 16.

The method by which the bowl construction of the invention is manufactured is exemplified in FIG. 4. While the manufacture may no doubt be carried out by different specific mechanisms, it is preferred to follow this example in an assembly line-type technique. Firstly, a vertically disposed arbor 30 is provided having an upwardly-projecting tapered extremity 32 of reduced diameter, the beginning edge of which forms an annular shoulder 34. In the manufacture of the pipe bowl, the eyelet 24, initially provided with its collarlike end enlargement 28 already formed, is dropped into place over the extremity 32 at the end of the arbor, with the enlarged head 28 of the eyelet resting against the shoulder 34 of the arbor. That is, the hollow cylindrical passage through the eyelet encircles and receives the extremity 32, preferably by serially advancing the eyelets to a predetermined position in an automated manner, at which point the arbor 30 is raised to pick up each eyelet when the same arrives at such position. Next, the fire-resistant inner plate element 20 is picked up from a predetermined position by the rising arbor and eyelet, with the elongated barrel portion of the eyelet passing through the central aperture in the annular plate element. Following this, the bowl member 12 is placed over the upright arbor, eyelet, and plate element 20 (or, alternatively, is picked up by this assembly of arbor, eyelet, and plate), with the upwardly-extending shank or barrel of the eyelet passing upwardly through the opening in the bottom wall of the bowl member. Following this, the outer reinforcing plate element 22 is picked up over the part of the barrel of the eyelet 24, which protrudes outwardly beyond the bottom wall 16 in the same manner as the other components just described, following which only a small extent of the eyelet barrel protrudes outwardly beyond the outer plate.

As will be understood, the basic assembly of the bowl components just described can readily be accomplished by automated equipment in a very rapid manner. The final step in the assembly process is the downward excursion of a generally tubular plunger member 36, which comes into contact with the brief protruding extremity of the eyelet barrel, noted above. Plunger 36 applies downward pressure against the end of the eyelet barrel, in opposition to the arbor 30, and this pressure together with a rotary motion imparted to the plunger with respect to the arbor forms the outer enlargement 26 of the eyelet described hereinabove. That is, the protruding portion of the eyelet barrel becomes laterally enlarged into a collarlike formation, in a manner generally referred to as "spinning" the eyelet. Thus, the entire assembly and manufacture of the completed bowl construction according to the invention can be done in a very rapid and fully automated manner, producing corncob bowls for smoking pipes which have an absolutely strong and very long-lasting bottom extremity that will amply withstand the elevated temperatures created during smoking, as well as the customary scraping and other similar abusive treatment normally encountered.

It is entirely conceivable that upon examining the foregoing disclosure, those skilled in the art may devise particular embodiments of the concepts forming the basis of the invention

which differ somewhat from the preferred embodiment shown and described herein, or may make various changes in structural details to the present embodiment. Consequently, it is to be recognized that the preferred embodiment shown and described is for purposes of general illustration only and is in no way intended to illustrate all possible forms of the invention.

I claim:

1. A bowl construction for a smoking pipe, comprising: a bowl member having a side wall and a bottom wall, together defining a hollow interior cavity; said bottom wall having an aperture therein; a perforate plate element of heat-resistant material disposed within said cavity and above said bottom wall, said plate having an opening therein aligned with said bottom wall aperture; and a fastener means having a portion disposed within said aligned bottom wall aperture and plate element opening, said fastener means securing said plate in place with respect to said bottom wall.

2. The bowl construction for smoking pipes of claim 1, wherein said fastener means has a longitudinal axis coincident with the axis of said aligned aperture and opening, and lateral enlargement portions engaging said plate element and said bottom wall.

3. The bowl construction for smoking pipes of claim 2, wherein said fastener means extends through both said plate element and said bottom wall, and said enlargement portions are located above said plate and below said wall to sandwich the same together.

4. The bowl construction for smoking pipes of claim 3, wherein said fastener means comprises a generally tubular member.

5. The bowl construction for smoking pipes of claim 1, wherein said perforate plate is an annular disk.

6. The bowl construction for smoking pipes of claim 5, wherein said fastener means extends through both said disk and said bottom wall and has lateral projections engaging said disk and bottom wall to hold the two together.

7. The bowl construction for smoking pipes of claim 1, further including a reinforcement plate member disposed beneath said bottom wall and attached to said fastener means to anchor the same.

8. The bowl construction for smoking pipes of claim 7, wherein said reinforcement plate has an opening through it disposed in alignment with said bottom wall aperture and said plate element opening, said fastener means extending through all of said aligned openings and aperture.

10 9. A method of manufacturing bowls for smoking pipes, comprising the steps:

providing a bowl member having side and bottom walls and an opening in said bottom wall;
positioning a heat-resistant plate element within said bowl and adjacent said bottom wall; and
attaching said plate element to said bottom wall by a fastening means inserted through said bottom wall opening and secured in such position.

10 10. The method of claim 9, wherein said fastening means is secured by the step of enlarging at least one of its end extremities.

11. The method of claim 9, further including the step of placing a reinforcement plate against the outside of said bottom wall and securing the same in place by said fastening means.

12. The method of claim 11, wherein said fastening means is secured by the step of forming enlargements at both of its ends immediately beyond said plates, thereby sandwiching said plates and bottom wall together.

13. The method of claim 12, wherein both of said plates have apertures and said fastening means comprises a generally tubular eyelet element having one enlarged end, said steps comprising aligning said plate apertures with said bottom wall opening, passing the other end of said eyelet element through said aligned apertures and opening, and enlarging said other eyelet end adjacent one plate to sandwich the plates and bottom wall together.
